UNITED STATES PATENT OFFICE.

HARRY O. DAVIDSON, OF CLEVELAND HEIGHTS, OHIO, ASSIGNOR TO THE HYDRAULIC
PRESSED STEEL COMPANY, OF CLEVELAND, OHIO, A CORPORATION OF OHIO.

CONCRETE-FORM.

1,287,573.

Specification of Letters Patent. Patented Dec. 10, 1918.

Application filed April 8, 1915. Serial No. 20,061.

To all whom it may concern:

Be it known that I, HARRY O. DAVIDSON, a citizen of the United States, residing at Cleveland Heights, in the county of Cuyahoga and State of Ohio, have invented a certain new and useful Improvement in Concrete-Forms, of which the following is a full, clear, and exact description, reference being had to the accompanying drawings.

10 This invention relates to forms for molding concrete, and more particularly to forms that are employed for the purpose of producing cylindrical objects, such as silos. It is the general purpose of the invention to produce a form of this kind which can be readily assembled and disassembled and which is readily adjustable whereby changes in curvature may be conveniently accomplished. Further and more limited objects 15 of the invention will appear hereinafter in connection with the detailed description.

In the drawings forming part hereof, Figure 1 represents a view, partly in plan and partly in transverse section, of a silo mold constructed in accordance with my invention; Fig. 2 a detail in perspective of the interior of the mold; Fig. 3 a vertical sectional view through the mold; Fig. 4 a sectional detail illustrating the manner of 20 clamping the inner mold plates; and Fig. 5 a sectional detail illustrating the manner of securing the "liners" to the uprights.

The form comprises generally a plurality of upright posts or ribs which form a support for the inner plates of the mold and means associated with such uprights for clamping the plates thereto; also a plurality of plates which may be connected to form the outer shell of the mold, both the 25 inner and the outer plates preferably being flexible whereby their contour may be changed to produce cylindrical or segmental objects of varying diameter; and also horizontal liners which connect the upright posts or ribs.

Describing by reference characters the various parts illustrated herein, A denotes generally a plurality of upright posts which support the inner plates of the mold, indicated generally at B. These upright posts A are connected by means of the liners C, said liners being made each of a plurality of curved segments which are adapted to telescope at their ends. D denotes generally

the inner portion of the chute for the ensilage, this chute being of tunnel form in section and being provided with a special arch-shaped vertical series of plates E.

The outer shell comprises a plurality of curved plates F which are provided with means whereby they may be united to form a segmental or cylindrical wall surrounding the corresponding inner mold wall and having a special curved plate G coöperating with the plate E to form therewith a mold for the ensilage chute. The inner plates may be shifted upwardly by hand after each course of grouting has set, but the outer series, being joined together, will be lifted as a whole and, for this purpose, derricks 70 (indicated generally at H) are carried by the posts or ribs A and are provided with the usual blocks and falls for the purpose of lifting the outer wall.

The posts, indicated generally at A, are formed of two metallic members one of which is substantially channel-shaped in section and comprises a substantially flat web 1 having divergent sides 2 terminating in out-turned flanges 3, these flanges being united by the second member 4 which is connected thereto. These posts are made in suitable lengths which lengths may be connected to form a post of any desired height, as by means of the channel splices K—see 85 Figs. 2 and 3. These channel splices are shaped to receive therewithin the abutting end portions of the post members and may be connected thereto by means of bars 5 which may be identical with the bars shown 90 in Fig. 5, said bars having each a body which is conveniently formed from two metal straps suitably joined together and each having a bottom flange, as shown at 6, whereby a foot is provided. This foot 95 may be inserted into the post through the enlarged portion of one of the key hole slots 7 with which the posts are provided, the bar being movable into the narrow part of the slot, whereby the foot may engage the 100 inner face of the web 6 in a well known manner. Each bar is provided with a slot for the reception of a wedge key 7 by driving which a firm connection will be made, by means of the clamp K, between the post 105 sections.

The flanges 3 on the posts form a support for the edges of the mold plates B adjacent

thereto. Each plate is shown as provided at each lateral edge with a metal plate extension which is bent to conform to one of the tapered sides of the post A and to seat 5 upon the flange 3 thereof. 8 denotes the part of this plate extension which coöperates with the inclined side of the post adjacent thereto and 9 the part which is adapted to engage the flange 3. 10 denotes the 10 portion of this extension which is secured to the body of the plate B. It will be noted that the parts are so proportioned that, when the portion 9 is in engagement with the flange 3, a portion 8 will be substantially 15 in engagement with the side of the post and the plate B will be in substantial alignment with the plate 4.

To secure the mold plates to the post, I 20 may employ a yoke 11 the ends whereof are adapted to extend on opposite sides of the post and to engage the parts 9 of the mold plate extensions. This yoke may be secured in place by means of a bar 12, which may be similar to the bar 5 except that it 25 has two pairs of feet 13 and 14 projecting therefrom, the first mentioned pair being adapted to engage the inner face of the web 1 when the yoke is in its clamping position, indicated in Fig. 4, and the second being 30 adapted to engage the inner face of the web when the yoke is withdrawn and turned at right angles to the post so that its ends or feet engage said post. The yoke is locked in either of these positions by means of the 35 wedge key 15. This construction of yoke and clamping bar is shown, described and claimed in the application of Stewart R. McKay No. 872,648 filed November 17th, 1914. The plates B, as stated hereinbefore, 40 are of metal, but are sufficiently flexible or resilient to permit them to be bent more or less without injury, thereby accommodating these plates to silos or similar bodies of varying diameter. A sufficient number of 45 these plates and posts will be employed to produce a segmental body, leaving a space for the chute.

I prefer to form the inner wall of the chute mold in the manner shown in detail in 50 Fig. 1. B' denotes a pair of short angular plates the ends whereof are connected to the posts which are adjacent to the chute opening and to a pair of posts A', which are identical with the posts A but are located 55 within the chute opening or extension with their backs or webs 1 opposed to each other. Because of the absence of liners from the chute portion of the form, the posts A' are braced apart by means of struts 16. B² de- 60 notes an arch-shaped plate the ends whereof are connected to and supported by the ribs A' in the same manner as the ends of the plates B are connected to and supported by the posts A. This arch-shaped plate is pro- 65 vided with suitable strengthening ribs 17

and with inclined braces 18 connected to the arched and end portions of this rib.

Reference has been made to the "liners" C. A suitable number of these liners will be employed for the purpose of supporting and 70 properly alining the posts or ribs A. Each liner consists of a plurality of segments, each segment being shown as of channel shape having the flanges 19 presented inwardly or toward the center of the mold 75 while the web 20 is adapted to engage the posts or ribs A. These liner segments may be recessed, as indicated at 21 Fig. 5, to coöperate with the posts A, and may be secured in place by means of the bolts 5 and wedge 80 keys 7 which coöperate each with thrust plates 22 of channel shape which may be spot-welded to the liner (either to the inside or the outside thereof) and in line with the recesses 21.

As previously stated, the inner portion of the mold will be shifted, plate by plate, from a lower to a next higher level, after the grouting has set or hardened sufficiently. It is intended, however, to lift the outer mold 90 section as a whole or unit. This outer section will now be described. It is composed generally of a series of plates F each having at its lateral edges angle irons 24 whereby adjacent plates may be connected by means 95 of bolts 25. Each plate will preferably be provided with a ring 26 which is adapted to receive the hook of a fall. The plates F are sufficiently resilient or flexible to enable them to be used in forming the outer 100 sections of molds of varying diameter. If the plates were heavy and rigid, the curvature initially given to them could not be altered and, if the number of plates constituting the outer mold section were increased 105 or diminished, a corresponding distortion of shape in the mold would result. By making these curved plates flexible or resilient, a greater or less number of plates may be assembled, but the circular or cylindrical 110 contour can be preserved because of the resiliency of the plates.

A sufficient number of plates F will be employed to form the outer shell of the mold, with the exception of the chute portion. 115 This chute portion is provided by a special plate G, the central portion whereof is bent outwardly into arch form while the lateral edge portions thereof are outwardly concaved or reversely curved, as shown at 120 27. The plate G is provided with the angle irons 24 at its lateral edges whereby it may be secured to the angle irons carried by the lateral edges of the adjacent plates F. In order to give the proper shape to the chute 125 portion of the outer mold shell or wall, turnbuckles 28 are employed, each having one end connected to the arch portion of the plate G and its other end connected to a portion of the adjacent plate F. It will be evi- 130

dent that, by adjusting this turnbuckle, the curvature of the portions 27 may be varied and that thereby it is possible to produce a chute of substantially the same shape and 5 appearance in silos of widely varying diameter.

The key-hole slots with which the posts A are provided form a very convenient means for supporting the brackets which 10 carry the platforms for the workmen. Each bracket is shown as comprising an upper horizontal branch 29 and a lower inclined branch or brace 30 with an interposed strut 31. The branches 29 and 30 will be provided with suitable lugs having heads which 15 are adapted to enter the enlarged portions of a pair of the vertically spaced keyhole slots and to enable the brackets to be interlocked with the post by gravity, the heads 20 engaging the narrow bottom portions of the slots as the weight of the bracket carries them to the lugs of the bottom of the slots. These brackets are shown as supporting the platforms 32.

25 Each post A is adapted to support thereupon a derrick, indicated generally at H. The vertical post 33 of the derrick may be connected to the upper end of its post A by means of the same splice-clamp K that is 30 employed for uniting the other post sections. The horizontal arm 34 of the derrick extends across the top of the form and carries a block 35, the fall 36 whereof is shown as provided with a hook 37. When these hooks 35 are inserted into the appropriate rings 26, the outer mold section may be raised as a whole to the next level and may be supported by the derricks until the next succeeding operation.

40 Having thus described my invention, what I claim is:—

1. In a form of the character described, the combination of a series of posts, a pair 45 of posts offset from said series and located respectively adjacent to the first and the last post of the series, curved plates independent of the posts extending between and adapted to be secured to the posts in said series and forming a segmental wall, plates extending 50 between the first and last posts of the series and the offset posts, and a plate extending between and connected to the offset posts.

2. In a form of the character described, the combination of a series of posts, a pair 55 of posts offset from said series and located respectively adjacent to the first and the last post of the series, plates independent of the posts extending between and adapted to be secured to the posts in said series and forming a segmental wall, and a curved plate ex- 60 tending between and connected to the pair of offset posts.

3. In a form of the character described, the combination of a series of posts arranged 65 in substantially circular formation, plates

independent of said posts and interposed between all of the posts except the first and the last post of the series, an outwardly curved plate interposed between the first and the last post of the series, the said plates and 70 posts constituting an inner mold wall having an outwardly projecting chute or chamber between such first and last posts, and an outer mold wall surrounding the inner wall and having a curved section corresponding 75 to the outwardly curved plate between the first and the last post of the series.

4. In a form of the character described, the combination of a series of posts, a pair 80 of posts offset from said series and located respectively adjacent to the first and the last post of the series, curved resilient plates extending between and secured to the posts of said series and forming a segmental wall, an angular plate having one branch secured to 85 the first post of the series and its other branch secured to the adjacent offset post, a second angular plate having one branch secured to the last post of said series and its other branch secured to the other offset post, 90 and a curved plate having its ends secured to said offset posts.

5. In a form of the character described, the combination of a series of posts, a pair 95 of posts offset from said series and located respectively adjacent to the first and the last post of the series, plates extending between the posts of said series and forming a segmental wall, bent plates extending between the first and the last posts of the series and 100 the offset posts, a plate interposed between said offset posts.

6. In a form of the character described, the combination of a series of posts, segmental curved liners connected to said posts, 105 curved resilient plates interposed between said posts, and a series of curved resilient plates connected together at their lateral edges and surrounding and spaced from the said posts and the first mentioned series of 110 plates.

7. In a form of the character described, the combination of a series of posts, curved plates independent of the posts interposed between and secured to the posts of said series, a pair of posts offset from said series and located respectively adjacent to the first and the last post of the series, plates interposed between the first and the last post of the series and the offset posts, a curved plate 115 interposed between the offset posts, and braces or struts interposed between said offset posts.

8. In a form of the character described, the combination of a series of posts, resilient 120 curved plates independent of the posts interposed between and secured to the posts of the series, a pair of posts offset from said series and located respectively adjacent to the first and the last post of such series, bent 125 plates

plates interposed between the first and the last post of the series and the offset posts, an arch shaped plate interposed between and having its ends connected to the offset posts, 5 and braces or struts interposed between said offset posts.

9. In a mold of the character described, the combination of an inner mold member comprising a series of posts and a series of 10 curved plates connected to said posts and adapted to form a segmental body with a lateral chute projection, and an outer mold member comprising a series of curved resilient plates having their lateral edges connected and arranged substantially concentric with the inner series and having a chute 15 projection spaced from the corresponding projection of the inner mold member, and means connected with such chute projection 20 of the outer mold member for varying the contour thereof.

10. In a mold of the character described, the combination of an inner mold member comprising a series of curved resilient plates 25 arranged to form a segmental body with a lateral chute projection, vertical posts supporting the lateral edges of said plates, an outer mold member comprising a series of curved resilient plates having their lateral 30 edges connected and arranged substantially concentric with the inner series and having a chute projection spaced from the corresponding projection of the inner mold member, and means connected with such chute 35 projection of the outer mold member for varying the shape thereof.

11. In a mold of the character described, the combination of a pair of mold plates, a 40 resilient plate interposed between said plates and having a portion projecting out of the line of said plates, and adjustable means connecting the projecting portion with the first mentioned plates whereby the contour of such portion may be altered.

12. In a mold of the character described, the combination of a pair of mold plates, a 45 resilient plate interposed between said plates and having an arch portion projecting out of the line of said plates, and adjustable 50 means connected between the arch portion and the plate whereby the contour of such portion may be altered.

13. In a mold of the character described, the combination of a segmental mold wall, a 55 resilient plate interposed between the ends of said wall and forming one of the mold walls for a chute, and means for varying the contour of such chute wall.

14. In a mold of the character described, 60 the combination of a pair of curved plates, a resilient plate interposed between the first mentioned plates and having its central portion projecting beyond said plates and connected thereto by a reversely curved portion 65 of such resilient plates, and means adjust-

ably connecting such projecting portion with the first mentioned plates whereby the curvature of the projecting portion may be varied.

15. In a mold of the character described, 70 the combination of an inner member comprising a series of curved plates arranged to form a segmental body with an arched extension, an outer mold member comprising a 75 plurality of curved plates adapted to be arranged substantially concentric with the circular portion of the inner member, the outer member having a resilient plate shaped to form an extension spaced from the extension of the inner member, and means adjustably connecting the sides of such projecting portion with the curved plates adjacent thereto.

16. In a mold of the character described, the combination of an inner member comprising a series of curved plates arranged to 85 form a circular body with a chute extension, an outer mold member comprising a plurality of curved resilient plates adapted to be arranged substantially concentric with the circular portion of the inner member, the 90 outer member having a resilient plate adapted to form a chute extension spaced from the chute extension of the inner member, and means adjustably connected to the sides of such outer chute extension to vary the 95 contour thereof.

17. In a mold of the character described, the combination of an inner member having a circular portion and an outwardly 100 projecting extension arranged to form the inner wall of a chute, an outer member having a circular portion adapted to be placed substantially concentric with the circular portion of the inner member and having a 105 resilient plate with its central portion projecting outwardly to form the outer wall of a chute the lateral portions of said plate being concave, and means adjustably connecting the outwardly projecting sides of the last mentioned plate with the circular portion whereby the concavity of the lateral portions of the intermediate plate may be varied.

18. In a mold of the character described, the combination of a pair of spaced plates, 115 a resilient plate interposed therebetween and having a central portion which is out of line with such spaced plates and having concaved lateral portions extending between the central projecting portion and such adjacent plates, and means adjustably connected with each side of the projecting portion of the intermediate plate and one of the adjacent plates and extending across the concaved portion of such intermediate plate.

19. In a mold of the character described, 120 the combination of a pair of spaced plates, a resilient plate interposed therebetween and having a central portion which is out of line with such spaced plates and having concaved 125

lateral portions and adjustable means for varying the concavity of such lateral portions of said resilient plate.

20. In a mold of the character described, 5 the combination of a pair of spaced plates, a resilient plate interposed therebetween and having a central portion which is out of line with such spaced plates and having concaved lateral portions interposed between 10 the central projecting portion and such adjacent plates, and turn buckles connected with each side of the projecting portion of the intermediate plate and one of the adjacent plates and extending across the concaved portion of such intermediate plate.

21. In a mold of the character described, the combination of a post having a lateral flange and a tapered side, a mold plate having a lateral extension which is adapted to 20 conform to said tapered side and to said lateral flange, and means carried by the posts

for clamping the flange-engaging portion of such extension against said flange.

22. In a mold form of the character described, the combination of a hollow post 25 having tapered sides and laterally projecting flanges, a pair of mold plates each having a lateral extension one portion whereof conforms to the tapered face of the post and another portion whereof conforms to and 30 is adapted to engage the adjacent lateral flange of said post, and clamping means carried by the post and adapted to engage the flange engaging portions and the lateral extensions of the said plates. 35

In testimony whereof, I hereunto affix my signature in the presence of two witnesses.

HARRY O. DAVIDSON.
